METHOD OF PREVENTING PARAFFIN
DEPOSITS IN OIL WELLS

Elmer F. Price, Borger, Tex.

Application January 30, 1942, Serial No. 428,809

1 Claim. (Cl. 166—21)

In the operation of oil wells in "paraffin territory," i. e., in fields yielding paraffin base oils, difficulties are invariably experienced in maintaining a continuous delivery of oil at a constant rate due to clogging of the pump tubing of the wells through accumulation of paraffin therein. In fact it is quite common for the paraffin to form in the inside of the tubing until scarcely sufficient clearance is left for the movement of the "sucker" or pump rods of the wells, so that ordinarily it is necessary to completely remove the tubing for cleaning sometimes as often as every thirty days. This is not only a laborious, time-consuming and therefore expensive procedure, but entails idling of the wells over correspondingly protracted periods. Such paraffin accumulation I have found to result from the action of electric currents set up in the presence of magnetic forces in and around the wells, or through generation of electricity by friction between the moving parts of the well pumping machinery.

My invention has for its aim to overcome the above drawbacks, that is to say, to preclude formation of paraffin by electrical or magnetic action so that a constant and uniform yield of oil from the wells may be maintained at all times. This objective I realize in practice as hereinafter more fully disclosed, by insulating the various parts of the pumping apparatus from each other and the ground at such points and in such manner as to prevent the possibility of electric current flow between them and the earth.

In the attached drawing.

Fig. 1 is a broken out view partly in elevation and partly in section, of an oil well and the pumping unit associated therewith, suitably arranged for the purposes of my invention.

Fig. 2 is a fragmentary view on a larger scale corresponding generally to Fig. 1 and showing to better advantage, important structural details at the upper portion of the well.

Fig. 3 is a cross sectional view taken as indicated by the angled arrows III—III in Fig. 2.

Fig. 4 is a fragmentary detail view in the region of the coupling of the "sucker" rod of the pumping unit with the connecting cables which extend to the head of the walking beam of said unit; and

Fig. 5 is a sectional view taken as indicated by the angled arrows V—V in Fig. 4.

The well and the associated pumping unit herein illustrated for convenience of exemplifying my invention, generally speaking, is of

well known construction, its metallic tubular casing being generally designated by the numeral 1. As ordinarily, the casing 1 extends above the ground level G, and is closed at the top by a head in the form of a cap 2, which, in this instance, is threadedly connected to said casing, see Fig. 2. Extending axially down through a central opening in the cap 2 is a tube 3 through which the oil is drawn from the well by means of a pump 5 at the bottom end of said tube. Extending laterally from the tube 3 above ground is a pipe line 6 which may lead to any convenient disposal for the pumped oil. The "sucker" rod 7 of the pumping unit passes through a stuffing box 8 at the protruding top end of the tube 3 and passes down through the latter to the pump 5, likewise in the usual way. Clamped to the upper end of the "sucker" rod 7 is a cross head 9, which, by means of a pair of flexible members 10 or cables 10, is connected to the "horse" head 11 on the counterbalanced walking beam 12 of the pumping jack which is comprehensively designated by the numeral 13. In accordance with accepted practice in the art, the beam 12 is fulcrumed about a fixed pivot 14, on the "Samson" post 15 of the pumping unit 13 and is rocked through a pitman 16 by a crank 17 on a rotary shaft 18, which, through suitable speed reduction means (not illustrated), is driven by an enclosed motor 19. The gases accumulating in the well and in the casing 1 are carried off through a valve controlled pipe 20 which leads laterally from said casing at a point slightly above the ground level G, see Figs. 1 and 2.

In order to adapt a well of the type briefly described above to the purposes of my invention, I make provisions as follows: Clamped to the tube 3 at intervals of its length and preferably over the couplings which join its component sections, are split spacing collars 21 whereof the component halves are connected by spring rings 22 fitting into circumferential grooves at opposite ends of said halves. As conventionally indicated, the collars 21 are fashioned from insulating material, preferably wood, to a diameter slightly less than the bore of the well casing 1, see Figs. 2 and 3, so that the gases may freely pass up around them. By virtue of their position, the collars 21 serve to maintain the tube 3 centralized in the well casing and also to prevent metallic contact between said tube and said well casing. To similarly prevent metallic contact between the head cap 2 and the well casing 1, the opening in said cap is bushed with insulation as at 25, and a washer 26 of insulation is interposed between

said cap and the top end of said casing. The sections of the oil delivery pipe 6 are electrically isolated, one from the other, through interposition of an insulation gasket 27 between the flanges 28 of the uniting coupling 29 and through use of insulation sleeves 30 and washers 31 in association with the clamp bolts 32 for said coupling. Like provisions may be made in the couplings (not shown) used to connect component sections of the gas draw-off pipe 28. Finally to preclude the metallic contact between the upper end of the sucker rod 7 and the clamp head 9, I interpose an insulating bushing 35 and apply an insulating washer 36 immediately above said head. To insure against slippage of the clamp head 9 on the rod 7, I apply immediately above the latter, a supplemental split metallic clamp collar 39 of which the halves bear directly against the rod. In addition a sleeve 40 of insulation is applied around the upper end of the sucker rod 7 at the region where it might possibly contact with the

horse head 11 of the walking beam 12 of the pumping unit 13.

From the foregoing it will be seen that through the interposition of insulation at the various regions and in the manner shown and described, I positively preclude the flow of electric current between the earth and the parts which constitute the well casing and the pumping apparatus, and in this way effectively prevent the formation of paraffin within the flow passages so that a constant and uniform delivery of oil is maintained at all times.

Having thus described my invention, I claim:

The method of preventing paraffin deposits in an oil well provided with a well casing, an oil production tubing within said casing, and a pump at the lower end of the tubing, which comprises precluding the flow of electric current between the pump and tubing on the one hand and the well casing and the ground on the other.
